UNITED STATES PATENT OFFICE.

HOHSON S. SHIMIZU, OF CHICAGO, ILLINOIS, ASSIGNOR TO ROBERTS & SCHAEFER COMPANY, OF CHICAGO, ILLINOIS, A CORPORATION OF ILLINOIS.

COAL-HANDLING PLANT.

1,335,531.

Specification of Letters Patent. Patented Mar. 30, 1920.

Application filed May 18, 1918. Serial No. 235,234.

To all whom it may concern:

Be it known that I, HOHSON S. SHIMIZU, a subject of the Emperor of Japan, residing at Chicago, in the county of Cook and State 5 of Illinois, have invented a certain new and useful Improvement in Coal-Handling Plants, of which the following is a specification.

My invention relates to coal handling 10 plant and associated parts and apparatus, and has for one object to provide a new and improved form of coal handling device, which will take the coal as it is dumped from the coal car, measure it, carry it up 15 and store it in a storage bin whence it may be discharged into the locomotive tender for coaling locomotives. Among the objects of my invention are to provide a smooth running satisfactory device of the so called 20 shallow pit type wherein a minimum amount of adjustment and repair is necessary, and wherein a pit of minimum depth may be used. Many other objects will appear from time to time in my specification. The invention is illustrated diagrammatically in 25 the accompanying drawings, wherein—

Figure 1 is a side elevation in part section of the whole apparatus with much of the plant omitted for clearness;

Fig. 2 is a section on an enlarged scale 30 along the line 2—2 of Fig. 1;

Fig. 3 is a side elevation in part section of the receiving and measuring apparatus and associated parts at the lower end of the 35 hoisting system;

Fig. 4 is a view similar to Fig. 3 showing the parts in a different position;

Fig. 5 is a detail of the hoisting bucket as it dumps;

Fig. 6 is a section along the line 6—6 of 40 Fig. 4.

Fig. 7 is a plan view of the cradle with parts in section along the line 7—7 of Fig. 8, showing the hoisting bucket rollers in 45 position of rest thereon by dotted lines;

Fig. 8 is a section along the line 8—8 of Fig. 7.

Fig. 9 is a section along the line 9—9 of Fig. 8.

Fig. 10 is a detail showing part of the 50 guide track.

Like parts are indicated by like characters in all the drawings.

A is a working pit, A¹ a shed covering it 55 containing incoming and unloading tracks

A². A³ is a hoisting tower leading up from the pit A and the shed A¹. A⁴ is the storage bin, having discharge chutes A⁵, A⁶ which may be manipulated to discharge coal into a locomotive tender on the tracks A⁶, 60 A⁷. A⁷ is a spiral staircase leading upwardly along the tower A³ from the ground to the motor room A⁸ at the top. A⁹ is an electric motor driven hoisting winch or hoist of any suitable type. It is adapted to move 65 the hoisting bucket A¹⁰ up and down, the track A¹¹ on the tower. In the present instance I have shown it as a friction drive, wherein a hoisting cable A¹² passes over sheaves A¹³ A¹⁴, the cable having a counter 70 weight A¹⁵ at one end and being attached to the bucket A¹⁰ at the other end. The bucket is of course expected to be filled or loaded from the side A¹⁶ but it discharges through the port A¹⁷. This port A¹⁷ is 75 closed by a combined chute and door A¹⁸ pivoted at the lowest point of the bucket in such manner that when it opens it causes the contents of the bucket to discharge at one 80 side of the path thereof. This door is held shut while the bucket is traveling because the roller A¹⁹ engages a track A²⁰ running up parallel with the bucket track, as shown in Figs. 1 and 4 for instance. When the bucket reaches the upper end of its excursion the track terminates in a short section A²¹ at right angles to the path of the bucket. The roller travels out along this path and the door is open. It sometimes happens 85 however that the bucket goes up a little farther than it is intended to, and in order to prevent the door from swinging down too far, the links A²² are provided. These links are pivoted on the bucket and slotted as at A²³ to engage pins A²⁴ on the bucket, so that 90 no interference is offered to the closure of the bucket, but the opening of the bucket too far is made impossible.

Located within the pit A, but terminating above the bottom thereof, is a hopper B, 100 into which the coal cars may discharge their load. This hopper has an inclined bottom, and terminates at the bottom in a discharge gate B¹. This gate is adapted to be closed by a sliding door B². This sliding door is 105 mounted upon rollers B³, adapted to travel along a track B⁴. B⁵ is a counterweight which normally holds the door in the upper closed position, the counterweight being connected by means of a cable B⁶ with the upper 110

- side of the sliding door. This door moves back and forth across the front of the gate along a line substantially normal to the path of material outwardly through the port, so that a minimum of resistance is offered to the closure of the door or gate, and so that the flow of material itself does not thrust against the gate and tend to open it or to hold it open. This gate is opened by 5 the downwardly moving bucket so that it opens as the bucket comes into register with the port as will farther on be pointed out. These tracks B^4 are mounted upon a framework B^7 , B^8 , which framework is in turn 10 mounted upon tracks B^8 , B^9 . These tracks B^8 , B^9 extend upwardly from near the bottom of the pit A up to the base of the tower A³. Immediately below the base of the tower A³ they are curved as indicated at B^{10} , B^{11} , until 15 just at the bottom of the tower a tangent to them, is a vertical line parallel with the track A¹¹. Guard tracks B^{12} , B^{13} are above the tracks B^8 , B^9 and are associated with them so as to form channels to guide rollers 20 B^{14} , B^{15} , which support a cradle B^{16} . These tracks B^8 , B^9 , B^{12} , B^{13} are mounted upon a framework or structure B^{17} in the bottom of the pit. 25 The cradle B^{16} engaging the tracks B^8 , B^9 , 30 and held upon them by the guard rails as indicated, is constrained to a parallel motion, and when the cradle travels down these tracks it moves over under the hopper B, but the cradle does not rotate, it merely comes 35 down and is moved to one side. This cradle has at one side thereof an upwardly extending track C, adapted to come into register with the track A²⁰, and form a continuation thereof. C¹, C² are cables extending up 40 over sheaves C², C³, C⁴ and terminating in counter weights C⁵ which tend normally to hold the cradle in the upper position immediately below the lower end of the track A¹¹. The track A¹¹ is made up of two parallel 45 channels between which travel rollers C⁶, C⁷ of the bucket A¹⁰. It will be noted that the rollers C⁶ only project a short distance into the space between the track channels, and the rollers C⁷ extend a long distance in. 50 These tracks A¹¹ are bent to the right as indicated in Fig. 4 over toward the hopper, and terminate in sections lines tangent to which are parallel with the tracks B^8 , B^9 where they pass under the hopper. The 55 flanges are cut away, however, at C⁸ so that the rollers C⁶ may pass straight through, but the rollers C⁷ will be guided over to the right. The cradle B^{16} is so arranged that when the bucket A¹⁰ is lowered the roller C⁶ 60 on the bucket will rest on the cradle B^{16} , and the same is true of the roller C¹⁰. The bucket will therefore be supported on the cradle in an upright position. As soon as 65 the load settles down on the cradle, the cradle travels down lifting up the counter-
- weight and moves over toward the right. The bucket is steadied and guided by the upper roller C⁷ giving a three point support for the cradle until the cradle rollers are in those parts of the tracks where they are parallel to each other. Then the cradle is constrained to a parallel motion, and at that time the roller C⁷ passes out away from the curved track portion, and is clear of the track altogether. As the cradle goes on 70 with its descent, it engages the upper edge of the gate and moves it down and the bucket gradually comes into register with the port discharging from the pit and the coal rushes in to fill the bucket. The bucket is so shaped 75 that only a predetermined quantity of coal may enter in, and when the bucket is filled the coal quits running. If the operator then hoists up on the bucket, the bucket would be moved up across the line of travel of the coal, the gate coming up to close off the coal, the bucket will gradually engage the tracks and when the cradle reaches the upper excursion the bucket will leave it and pass up 80 along the tracks.
- Great importance must be attached to the arrangement for starting the bucket and cradle down along proper lines. It will be noted at first that the curved tracks along which the two rollers of the cradle travel 95 are not parallel, and during that time the bucket which rests snugly on the cradle is still in engagement with the curved lower extension of the hoisting bucket tracks. Thus there is a three point support for positioning the bucket and cradle and preventing rotation, while permitting movement. As soon as the cradle rollers have reached 100 a part of the two tracks where they are parallel the cradle is held into parallelism by the engagement with the tracks and then 105 the bucket roller disengages or leaves the curved downward extensions of the hoisting tracks.
- It will be noted of course that the bucket 110 dump door is held shut first by the track running along parallel with the hoisting track and then by the extension on the cradle which is in continuation of the bucket holding track.
- It will be evident that while I have shown in my drawings an operative device, still many changes might be made both in size, shape and arrangement of parts without departing materially from the spirit of my invention, and I wish therefore that my drawings be regarded as in a sense diagrammatic. 115
- The rollers C¹⁰, C¹⁰ are guided to position of rest on the cradle by the two short tracks C¹¹, C¹¹ projecting up from the cradle B¹⁶. 120
- The use and operation of my invention are as follows:—
- Loaded coal cars are run on to the receiving tracks and they are then dumped in any suitable manner, and the hopper in the 125 130

pit is filled with the coal. The motor which controls the hoisting bucket is then put into operation, and this bucket is caused to reciprocate or travel up and down 5 from the top of the tower to the bottom. When the bucket is lowered the weight of the bucket as it rests upon the cradle, is sufficient to outweigh the counterbalance which normally holds the cradle up, and 10 the bucket and cradle will move down and to one side without rotation of the bucket but merely by a translation of it. As the bucket passes down into register with the discharge port or opening at the bottom of 15 the hopper, the cradle which has engaged the door, gradually forces that door down over-balancing the counterweight which tends normally to hold it up, the door being so positioned that as it opens, and as the coal 20 commences to flow, the coal will flow into the bucket. The bucket stays at the bottom of its excursion with the door wide open and the opening of the bucket in register with the opening of the hopper until the 25 coal has completely filled the bucket, and no further flow can take place. The operator then either by hand or by an automatic mechanism not here illustrated, starts the bucket up. As it goes up the door gradually closes off, traveling across the line of 30 travel of the coal column as it runs from the hopper to the bucket and the door finally completely closes off the flow of coal and the loaded bucket goes on up. When 35 the cradle reaches the upper end of its excursion, the bucket leaves it and goes on in a vertical direction until it reaches the top of the tower. At the top of the tower the door closing roller passes out on to the 40 horizontal extension of the holding track, the door opens forming a chute, the coal is dumped out and the bin is filled. By keeping count of the number of trips the bucket makes, you have an accurate record of the 45 amount of coal handled.

The operation so far as the movement of the bucket into and out of register with the hopper and so far as the opening and closing of the door is concerned, is entirely automatic, and requires no attention from the operator.

It will be noted that the hoisting engine is up at the top of the tower. It may be a steam engine or would be preferably an 55 electric motor as indicated. This electric motor might or might not be equipped with automatic machinery for reversing it to move the bucket back and forth. Probably it would be, but that forms no part of my 60 invention, and is so not illustrated.

It is necessary always to have a counterweight to balance the bucket when a single bucket is used, as is the case in this invention, and therefore the tower must be strong 65 enough to support the weight of the coun-

terweight and of the bucket. Moreover in actual practice the operating room being up at the top, is less likely to be infested by tramps and loafers, and that in railroad practice has developed into a very important phase of the situation. 70

The bucket is substantially balanced, but if it by any chance should be out of balance, or in order to make sure of absolute accuracy in running, the two rollers on each 75 side engaging the tracks forming a channel insures that the buckets will travel along the predetermined path. There will be of course a slight pressure on the sides, particularly when the bucket is loaded, caused 80 by the sliding of the door roller along the holding or closing track, but this pressure will be so slight as to be of no particular moment and can easily be cared for in the design. 85

I claim:—

1. In a coal handling plant a bucket having a discharge port, a pivoted closure therefor, tracks along which the bucket travels, a separate track parallel therewith engaging 90 and retaining the closure in closed position, a movable cradle adapted to engage the bucket at one end of its excursion along bucket tracks and to guide it away therefrom and means on the cradle for keeping 95 the closure closed.

2. In a coal handling plant a bucket having a discharge port, a pivoted closure therefor, tracks along which the bucket travels, a separate track parallel therewith engaging 100 and retaining the closure in closed position, a movable cradle adapted to engage the bucket at one end of its excursion along bucket tracks and to guide it away therefrom and a member on the cradle adapted 105 to be in register with the separate closure engaging track and keep the bucket closure in closed position.

3. A conveying bucket, vertical tracks along which it travels, a cradle adapted to 110 carry it, inclined parallel tracks along which the cradle travels, curved tracks extending upwardly toward the lower ends of the vertical tracks in continuation of the inclined tracks, rollers on the cradle, means 115 associated with said curved and inclined tracks for holding the rollers thereupon, rollers on the bucket adapted to engage the vertical tracks, curved tracks downwardly and sidewardly extending from the vertical 120 tracks adapted to be engaged by one of the rollers on the bucket to give a three-point support to hold the cradle and bucket against rotation until the cradle rollers reach the parallel portions of the inclined 125 tracks, the cradle tracks being more widely separated at the top than below.

4. The combination with a hoisting bucket of vertical tracks, means for moving it therealong, rollers projecting out- 130

- wardly from the bucket and engaging said tracks, the lower rollers being shorter than the upper, curved tracks extending downwardly and outwardly from the end of the 5 vertical tracks, the lower sides of the curved tracks being cut away to permit the shorter lower rollers to pass straight through, the upper rollers being of such length as to remain in operative engagement with the 10 curved tracks.
5. The combination with a hoisting bucket of vertical tracks, means for moving it therealong, rollers projecting outwardly from the bucket and engaging said 15 tracks, the lower rollers being shorter than the upper, curved tracks extending downwardly and outwardly from the end of the vertical tracks, the lower sides of the curved tracks being cut away to permit the shorter 20 lower rollers to pass straight through, the upper rollers being of such length as to remain in operative engagement with the curved tracks, a carriage for supporting and guiding the bucket downwardly and to one 25 side of the lower ends of the vertical tracks, the long rollers on the bucket being adapted to remain in engagement with the curved bucket tracks during the earlier portion of the movement of the carriage the bucket 30 being adapted to rest upon the carriage.
6. A coal handling plant comprising a receiving hopper having a discharge port, a hoisting and measuring bucket, means for moving it vertically toward and from the 35 hopper, separate means at the lower end of its excursion for moving it horizontally under the hopper into register with the port while continuing its downward movement, said last mentioned means including a plurality of parallel tracks, rollers supporting the bucket and means for maintaining said 40 rollers in the operative position upon the tracks said tracks being out of parallelism immediately adjacent their upper extremities and additional means for holding the bucket against rotation until the rollers have moved onto the parallel track sections.
7. A coal handling plant comprising a receiving hopper having a discharge port, a 45 hoisting and measuring bucket, means for moving it vertically toward and from the hopper, separate means at the lower end of its excursion for moving it horizontally under the hopper into register with the port 50 while continuing its downward movement, said means including a plurality of parallel tracks, rollers supporting the bucket and means for maintaining said rollers in the operative position upon the tracks, said 55 tracks being out of parallelism immediately adjacent their upper extremities and additional means for holding the bucket against rotation until the rollers have moved onto the parallel track sections, a cradle upon 60 which the bucket is adapted to rest as it ap- 65 proaches the lower end of its excursion, the bucket supporting rollers being mounted on said cradle.
8. A coal handling plant comprising a ported receiving hopper, a track extending vertically upward from the hopper, an inclined track extending beneath the hopper having an upwardly curved extension terminating below the lower end of the vertical track, a cradle adapted to travel along said 70 inclined track, means for holding it normally at the upper end thereof, a bucket arranged to travel along the vertical track and to rest upon the cradle when it is at the lower end of the vertical track, means for guiding and 75 steadyng the bucket and cradle as the two pass down along the inclined track from the vertical track, said means comprising a curved extension on the vertical track, a member on the bucket engaging it, said member adapted to come out of engagement with the curved extension after the bucket and cradle have completed a portion of their downward movement, there being a plurality of track engaging members on 80 the bucket only one of them being adapted to engage the curved extension, the others being arranged to be out of register therewith.
9. In a coal handling plant a bucket having a discharge port, a closure therein, means for holding the closure closed during the vertical travel of the bucket, a movable cradle adapted to receive the bucket at the lower end of its excursion and to move it 85 laterally, and means on the cradle for keeping the closure closed.
10. The combination with a hoisting bucket of a vertical track, means for moving the bucket therealong, parts projecting outwardly from the bucket and engaging the track, a curved track extending downwardly and outwardly from the lower end of the vertical track, a part on the bucket adapted to engage the curved track to move the 90 bucket laterally, additional curved tracks beneath said track adapted to receive and downwardly and outwardly to convey the bucket beyond the end of said track.
11. A coal handling plant comprising a 95 hopper having a discharge port, a bucket having an inlet port, means for moving the bucket vertically, means for allowing it to move from the vertical beneath the hopper at the lower end of its excursion so as to bring the two ports into register, and a cut-off gate adapted to move responsive to the bucket movement, and to leave a free passage from the hopper to the bucket while the ports are in register, said last mentioned 100 means including a plurality of parallel track rollers supporting the bucket, and means for maintaining said rollers in operative position upon the tracks.
12. A coal handling plant comprising a 105

- hopper having a discharge port, a bucket having an inlet port, means for moving the bucket vertically, means for allowing it to move from the vertical beneath the hopper 5 at the lower end of its excursion so as to bring the two ports into register, and a cut-off gate adapted to move responsive to the bucket movement, and to leave a free passage from the hopper to the bucket while 10 the ports are in register, said last mentioned means including a plurality of parallel tracks, rollers supporting the bucket, and means for maintaining said rollers in operative position upon the tracks, and a cradle 15 upon which the bucket is adapted to rest as it approaches the lower end of its excursion, the bucket supporting rollers being mounted on said cradle.
13. A coal handling plant comprising a hopper with a discharge port, a bucket with a receiving port, means for moving the bucket vertically, a track extending from one side of the vertical line of travel and along which the bucket moves to a point beneath the hopper discharge port, pairs of members of said track being more widely separated at the top than below, a cradle traveling on said track and adapted to receive and carry the bucket to one side and 25 to bring the two ports into register, and a cut-off gate between the ports adapted to be operated responsive to the said movement of the cradle so that when the ports are in register to leave free passage between them.
14. A coal handling plant comprising a hopper having a discharge port, a bucket having an inlet port, the two ports being in planes substantially parallel with each other, means for moving the bucket vertically, and means for allowing it bodily to move to the side beneath the hopper at the lower end of its excursion so as to bring the two ports into register, a cut-off gate between and substantially parallel with the 30 ports, adapted to move in response to the pressure of the bucket, and leave a free discharge from the hopper to the bucket while the ports are in register, the gate being engaged and moved by the bucket.
15. A coal handling plant comprising a hopper having a discharge port, a bucket having an inlet port, the two ports being in planes substantially parallel with each other, means for moving the bucket vertically, and means for allowing it bodily to move to the side beneath the hopper at the lower end of its excursion so as to bring the two ports into register, a cut-off gate between and substantially parallel with the 35 ports, adapted to move in response to the pressure of the bucket, and leave a free discharge from the hopper to the bucket while the ports are in register, a bucket engaging member on said cut-off gate, the translating means for moving the bucket 40 having a free and uninterrupted passage from the hopper to the bucket while the ports are in register, a bucket engaging member on said cut-off gate, the means for moving the bucket laterally comprising an inclined track adapted to direct the bucket beneath the hopper discharge port and against said bucket engaging member, said cut-off gate adapted to move along a path parallel to the path of the bucket.
16. A coal handling plant comprising a hopper having a discharge port, a bucket having an inlet port, the two ports being in planes substantially parallel with each other, means for allowing it bodily to move to the side beneath the hopper at the lower end of its excursion so as to bring the two ports into register, a cut-off gate between and substantially parallel with the ports, adapted to control the flow of coal from the hopper to the bucket and to move in response to the pressure of the bucket, and leave a free and uninterrupted passage from the hopper to the bucket while the ports are in register, a bucket engaging member on said cut-off gate, the means for moving the bucket laterally comprising an inclined track adapted to direct the bucket beneath the hopper discharge port and against said bucket engaging member, 50 said cut-off gate adapted to move along a path parallel to the path of the bucket.
17. A coal handling plant comprising a hopper having a discharge port, a bucket having an inlet port, the two ports being in planes substantially parallel with each other, means for allowing it bodily to move to the side beneath the hopper at the lower end of its excursion so as to bring the two ports into register and a cut-off gate between and substantially parallel with the ports, adapted to control the flow of coal from the hopper to the bucket and to move in response to the pressure of the bucket, and leave a free and uninterrupted passage from the hopper to the bucket while the ports are in register, a bucket engaging member on said cut-off gate, the means for moving the bucket laterally comprising a plurality of inclined tracks curved at their upper ends adjacent the vertically moving means, said tracks being adapted to direct the bucket beneath the hopper discharge port and against said bucket engaging member.
18. A coal handling plant comprising a hopper having a discharge port, a bucket having an inlet port, the two ports being in planes substantially parallel with each other, means for moving the bucket vertically, means for allowing it to move to the side under the influence of gravity beneath the hopper at the lower end of its excursion so as to bring the two ports into register and a cut-off gate between and substantially parallel with the ports, adapted to control the flow of coal from the hopper to the bucket and to move in response to the pressure of the bucket, and leave a free and uninterrupted passage from the hopper to the bucket while the ports are in register.

interrupted passage from the hopper to the bucket at all times, while the ports are in register, a bucket engaging member on said cut-off gate, the means for moving the bucket bodily laterally comprising a plurality of inclined tracks curved at their upper ends adjacent the vertically moving means, said tracks being adapted to direct the bucket beneath the hopper discharge port 10 and against said bucket engaging member and a cradle adapted to ride on said inclined tracks and to support the bucket.

19. A coal handling plant comprising a hopper having a discharge port, a bucket 15 having an inlet port, means for moving the bucket vertically, and means for allowing it bodily to move to the side beneath the hopper at the lower end of its excursion so as to bring the two ports into register, 20 a cut-off gate adapted to control the flow of coal from the hopper to the bucket and to move in response to the pressure of the bucket, and leave a free and uninterrupted discharge from the hopper to the bucket at 25 all times, while the ports are in register, a bucket engaging member on said cut-off gate, a laterally moving means comprising inclined tracks adapted to direct the bucket beneath the hopper discharge port and 30 against said bucket engaging member, a cradle adapted to ride on said inclined tracks and to support the bucket.

20. A coal handling plant comprising a hopper having a discharge port, a bucket 35 having an inlet port, the two ports being in planes substantially parallel with each other, means for moving the bucket vertically, means for allowing it bodily to move to the side beneath the hopper at the lower 40 end of its excursion so as to bring the two ports into register, and a cut-off gate between and substantially parallel with the ports, adapted to control the movement of coal from the hopper to the bucket to move 45 responsive to the bucket movement and to leave a free and open passage from the hopper to the bucket during the time when the ports are in register.

21. A coal handling plant comprising a 50 hopper having a discharge port, a bucket having an inlet port, the two ports being in planes substantially parallel with each other, means for moving the bucket vertically, means for allowing it bodily to move to the side under the influence of gravity beneath the hopper at the lower end of its excursion so as to bring the two ports into register and a cut-off gate between and substantially parallel with the ports, adapted 55 to control the movement of coal from the hopper to the bucket to move responsive to the bucket movement and to leave a free and open passage from the hopper to the bucket during the time when the ports are in register, said means for moving the 60

bucket laterally comprising a movable cradle and supporting tracks.

22. A coal handling plant comprising a hopper having a discharge port, a bucket having an inlet port, the two ports being 70 in planes substantially parallel with each other, means for moving the bucket vertically, means for allowing it bodily to move to the side beneath the hopper at the lower end of its excursion so as to bring the two 75 ports into register and a cut-off gate between and substantially parallel with the ports, adapted to control the movement of coal from the hopper to the bucket during the time when the ports are in register, said 80 means for moving the bucket laterally comprising a movable cradle and supporting tracks, and means for normally tending to hold the gate closed in opposition to the action of the bucket.

23. A coal handling plant comprising a hopper having a discharge port, a bucket having an inlet port, the two ports being substantially parallel with each other, 85 means for moving the bucket vertically, 90 means for allowing it bodily to move to the side under the influence of gravity beneath the hopper at the lower end of its excursion so as to bring the two ports into register, a sliding cut-off gate between and 95 substantially parallel with the ports adapted to control the movement of coal from hopper to bucket to move responsive to the bucket movement and to leave a free and open passage from the hopper to the bucket 100 during the time when the ports are in register.

24. A coal handling plant comprising a hopper having a discharge port, a bucket having an inlet port, the two ports being 105 in planes substantially parallel with each other, means for moving the bucket vertically, means for allowing it bodily to move to the side beneath the hopper at the lower end of its excursion so as to bring the two 110 ports into register and a cut-off gate between and substantially parallel with the ports, adapted to control the movement of coal from the hopper to the bucket to move responsive to the bucket movement and to 115 leave a free and open passage from the hopper to the bucket during the time when the ports are in register, said means for moving the bucket laterally comprising a movable cradle and supporting tracks having 120 vertical and lateral portions adapted to cause said cradle to move first vertically and then laterally in the inclined direction.

25. A coal handling plant comprising a hopper having a discharge port, a bucket 125 having an inlet port, the two ports being in planes substantially parallel with each other, means for moving the bucket vertically, means to move it bodily to the side under the influence of gravity laterally be- 130

neath the hopper at the lower end of its excursion so as to bring the two ports into register and a cut-off gate between and substantially parallel with the ports, adapted to control the movement of coal from the hopper to the bucket to move responsive to the bucket movement and to leave a free and open passage from the hopper to the bucket during the time when the ports are in register, said means for moving the bucket laterally comprising a movable cradle and supporting tracks, having vertical and lateral portions adapted to cause said cradle to move

vertically and then laterally in the inclined direction, the tracks over which the cradle travels being more widely separated at the upper ends than at the lower.

In testimony whereof, I affix my signature in the presence of two witnesses this 15 day of May 1918.

HOHSON S. SHIMIZU.
